CLAIM

The ornamental design for headphone and charger, as shown and described.

DESCRIPTION

FIG. 1 is a bottom, front, left side perspective view of headphone and charger, showing my new design;

FIG. 2 is an exploded front and right side perspective view of headphone and charger;

FIG. 3 is a top, rear, right side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings depict portions of the headphone and charger that form no part of the claimed design.
